[57] CLAIM

The ornamental design for a vehicular adaptor station for a portable communication device, as shown and described.

DESCRIPTION

FIG. 1 is an isometric view of one embodiment of a vehicular adaptor station for a portable communication device showing our new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof; and

FIG. 7 is a rear view thereof.

FIG. 8 is an isometric view of another embodiment of a vehicular adaptor station for a portable communication device showing our new design;

FIG. 9 is a front view thereof;

FIG. 10 is a left side view thereof;

FIG. 11 is a right side view thereof;

FIG. 12 is a top plan view thereof;

FIG. 13 is a bottom plan view thereof; and,

FIG. 14 is a rear view thereof.
